PRIME MOVER CONTROL SYSTEM

Arthur Rosch, Brieselang, near Nauen, Germany,
assignor to General Electric Company, a corporation of New York

Application September 8, 1938, Serial No. 229,021
In Germany October 4, 1937

5 Claims. (Cl. 60—6)

This invention relates to control means for drive systems in which a main prime mover is arranged for driving a machine during normal full load conditions and a separate auxiliary prime mover unit arranged to be connected through common gearing for driving the machine under partial load conditions.

In such power plant installations as are provided in ships or the like, an auxiliary prime mover unit is often arranged for driving the propeller or other driven machine at low speed or for light loads. For high speed operation or greater loads, the drive is transferred to a main prime mover unit and the auxiliary unit simultaneously disconnected and shut down.

It is an object of this invention to provide a new and improved arrangement for controlling the operation of the prime mover units with respect to each other so that the transfer of load from one unit to the other may be accomplished in a smooth and efficient manner.

For a consideration of what I believe to be novel and my invention, attention is directed to the following description and the claims appended thereto taken in connection with the accompanying drawing.

The single figure of the drawing illustrates in a diagrammatic form a power plant arrangement embodying my invention.

30 A main prime mover unit is shown in this instance as comprising an elastic fluid turbine 10 while the auxiliary prime mover unit is represented by an electric motor 11. The two prime mover units are arranged to be connected through 35 the common gearing 12 to the shaft 13 extending to the driven machine (not shown). The shaft 14 of the turbine is shown as being fast coupled with the common gearing 12 through the pinion 15. The shaft 16 of the electric motor, on the other hand, is provided with an overrunning clutch 17 arranged between the motor and the pinion 18 in engagement with the common gearing 12.

The supply of operating fluid through conduit 45 19 to the elastic fluid turbine 10 may be controlled by any suitable valve means 20. As shown, the stem of the valve is threaded in a collar 21 slidably arranged within a housing 22. The valve may be operated by any suitable motor means, or by a handwheel 23. The collar is normally retained in the position shown by a pivoted detent 24 bearing against a shoulder 25 of the collar. A spring 26 is arranged between the end wall of the housing 22 and the 50 collar 21 so that upon a releasing movement of

the detent 24, the collar will be forced to the right moving the valve 20 from the open to the closed position. The pivoted detent 24 is rigidly connected to two actuating arms 27 and 28 which are biased in counterclockwise direction against the stop 29 by the light spring 30. The detent is moved to the releasing position by means responsive to a predetermined speed of either of the prime mover units. The shaft 14 of the elastic fluid turbine is provided with a governor 31, of a well-known type, which upon a predetermined speed of the turbine will be thrown outwardly to engage with the finger 32 of the latch member 33. Upon the releasing movement of the latch 33, the bell crank 34 will be freed 10 for pivotal rotation in counterclockwise direction under the force of the spring 35 acting through the pivoted lever 36 and the connecting link 37. Simultaneously, the spring 35 acting through the link 38 will rotate the lever arm 28 in a clockwise direction, against the bias of spring 39, to move the detent 24 to the releasing position. The shaft of the electric motor is provided with a governor 39 adapted to engage with the finger 40 of the latch 41 upon the occurrence of a predetermined speed. Upon the release of the latch 15 20 the bell crank 42 will be freed for rotation in counterclockwise direction under the force of the spring 43 acting through the rod 44. The other end of the rod 44 is connected to rotate the lever arm 27 in clockwise direction and in turn move the detent 24 to the releasing position.

The electric motor 11 is arranged to be energized from a suitable source of supply 45 through leads 46 having a circuit breaker 47 connected 35 therein. The circuit breaker may be of any well-known type such as represented by the latch closed device shown having a tripping solenoid 48. Means are provided for automatically de-energizing the electric motor 11 upon a predetermined pressure of operating fluid admitted to the elastic fluid turbine 10 through the valve 20. As indicated, a pressure responsive device 49 mounted upon a stationary part 50 is in communication through the connection 51 with the 45 inlet chamber of the elastic fluid turbine. Upon the occurrence of a predetermined condition, the pressure responsive device is arranged to close an electric circuit across the contacts 52 and thereby energize the tripping solenoid 48 and disconnect 50 the motor 11.

The operation of the control system described is as follows: During standstill condition of the power plant, the valve 20 controlling the supply of operating fluid to the elastic fluid turbine 10 55

is closed and, accordingly, the pressure responsive device 49 will be in the open circuit position. The electric motor 11 may then be energized by actuating the switch 47 to the position shown. The shaft 13 will be driven through the clutch 17 and the gearing 12 for low speed or light load operation. Upon the increase of load, the elastic fluid turbine is energized by the opening of the valve 20. As the elastic fluid pressure builds up within the turbine inlet chamber, the pressure responsive device 49 will close the circuit across the contacts 52, thereby energizing the tripping solenoid of the circuit breaker 47 and deenergizing the electric motor 11. As the load is taken over by the turbine, and the speed of the motor drops below the speed of the pinion 18, the overrunning clutch 17 will be so actuated as to disconnect the motor 11 from the common gearing. Should the elastic fluid turbine due to the occurrence of some abnormal condition tend to race, the governor 31 thereof will trip the latch 33 to cause the closure of the elastic fluid admission valve 20. Should the overrunning clutch 17 fail to drop out and disconnect the motor 11 from the gearing 12 when the load is transferred to the turbine, the motor will be driven at an increased rate of speed by the turbine 10. Thereupon the governor 39 of the motor will trip the latch 41 to effect the closure of the elastic fluid admission valve 20. If it is desired to transfer the load from the turbine back to the motor for low speed operation, the valve 20 may be closed which will allow the closure of the motor control switch 47. As the speed of the gearing 12 and 18 drops to below that of the motor 11, the clutch 17 will engage and the transfer be completed.

Having described the principle of operation of my invention together with the apparatus which I now consider to represent the best embodiment thereof, I desire to have it understood that the apparatus shown is only illustrative and that the invention may be carried out by other means.

What I claim as new and desire to secure by Letters Patent of the United States is:

45. 1. In combination, a main driving unit, an auxiliary driving unit, common gearing for transmitting the power output of said units to a driven machine, an overrunning clutch between said auxiliary unit and said gearing for disconnecting said auxiliary unit upon said gearing being driven at a predetermined speed by said main driving unit above the speed of said auxiliary unit, means

for controlling the energization of said main driving unit, and means responsive to a predetermined abnormal speed of both of said units for deenergizing said main driving unit.

2. In combination, a turbine, an electric motor, common gearing for transmitting the output of said turbine and said motor to a driven machine, means between said motor and said gearing for disconnecting said motor from said gearing upon said gearing being driven at a predetermined speed by said turbine above the speed of said motor, and means responsive to a predetermined pressure of the operating fluid admitted to said turbine for deenergizing said electric motor.

3. In combination, an elastic fluid turbine, an electric motor, common gearing for transmitting the output of said turbine and said motor to a driven machine, means between said motor and said gearing for disconnecting said motor from said gearing upon said gearing being driven at a predetermined speed above the normal speed of said motor, valve means for controlling the admission of elastic fluid to said turbine, and means responsive to a predetermined speed of said electric motor for closing said valve means.

4. In a power plant having a main driving unit, and an auxiliary driving unit, means for controlling the power output of said units through common gearing to a driven machine comprising an overrunning clutch between said auxiliary unit and said gearing for disconnecting said auxiliary unit upon said gearing being driven at a predetermined speed by said main driving unit above the speed of said auxiliary driving unit, means responsive to a predetermined energization of said main driving unit for deenergizing said auxiliary driving unit, and means responsive to a predetermined excess speed condition of said auxiliary driving unit for deenergizing said main driving unit.

5. In a power plant having a main driving unit operatively connected to a driven shaft, and an auxiliary driving unit adapted to be connected to said driven shaft through clutch means, the combination comprising control means for said main driving unit, means responsive to the energization of said main unit for deenergizing said auxiliary unit, and means operative upon the occurrence of a predetermined abnormal condition of said auxiliary unit for effecting the deenergization of said main unit.

ARTHUR ROSCH.
